HANGER FOR A SEAL IN A FLOATING
ROOF TANKFrederick D. Moyer and Edward S. Fraser, Chi-
cago, Ill., assignors to Chicago Bridge & Iron
Company, a corporation of Illinois

Application February 5, 1947, Serial No. 726,468

8 Claims. (Cl. 220—26)

1

This invention relates to an improved seal hanger for use in conjunction with a floating roof of a liquid storage tank.

The seal hanger shown herein is an improvement upon the pending application for a seal hanger for a floating roof tank, filed by Frederick D. Moyer on the 3d day of February, 1947, as Serial No. 726,179.

As usually constructed, floating roofs for liquid storage tanks have a diameter less than the diameter of the tank in order that the roof may float freely upon the liquid stored. Means must necessarily be provided for sealing the annular space between the roof and the inner side walls of the tank to prevent excessive liquid loss through evaporation. It is customary to provide a plurality of shoes supported by the floating roof, and adapted to be pressed against the walls of the tank in a manner to seal the space between the shoes and the walls. An annular flexible seal between the shoes and the floating roofs seals the space existing therebetween. Numerous methods and apparatus have been devised to suspend the shoes against the tank wall, some being extremely complicated in their mechanism and difficult and expensive to fabricate.

We have invented and are herein disclosing and claiming a novel means for pressing the shoe against the tank walls, and suspending the same in proper relationship thereto.

The invention will be described with reference to the accompanying drawings in which:

Fig. 1 is a vertical section through a portion of a liquid storage tank and a roof floating therein showing the features of one embodiment of the invention;

Fig. 2 is a vertical section along line 2—2 of Fig. 1; and,

Figs. 3 and 4 are taken like Fig. 1 and show other embodiments of the invention.

Referring now to the drawings, 10 indicates the side wall of the liquid storage tank containing a liquid 11 upon which a floating roof 12 is supported. The floating roof is of any usual construction having a top portion 13, a bottom 14 and a side 15. Pivotally connected at 16 to the side of the roof is a lever, generally indicated 17, having a portion 18 extending downwardly from the point 16 to an angle 19, and a portion 20 extending inwardly from the angle. A weight 21 is provided to urge the portion 20 downwardly, and, therefore, to urge the angle 19 against the side 15 to press the same against the side of the tank. A shoe supporting member 22 is pivotally connected at 23 to the upper portion of the shoe,

2

the shoe supporting member in the embodiment shown in Fig. 1, being generally in the shape of an L having a vertical leg 24 and a horizontal leg 25. The horizontal portion 25 is pivotally connected to the portion 23 at 26, as shown. It is clear, however, that the member 22 may be attached to the shoe by means not necessarily pivotal, as, for example, by welding. In order to increase the strength and stability of the members just described, we prefer to construct them of parallel pairs of members, as shown in Fig. 2, hence there are two downwardly extending portions 18 and two portions 19 and 20 to make up the lever 17, and likewise there are two vertical portions 24 and two horizontal portions 25 comprising the shoe supporting member. The particular arrangement shown in Fig. 1 is, of course, duplicated about the periphery of the roof in order to support the shoes provided thereabout.

20 The parts are so constructed and arranged that the lower portion of the shoe 21 exerts an inward force against the lever 17 to elevate that lever from a freely hanging position when the roof is centered in the tank, the weight of the inwardly extending portion 20 together with the weight 21 exerting a corresponding an equal outward force against the bottom portion of the shoe. The lever 17 becomes further elevated from a freely hanging position upon a decrease 30 of the distance between the roof and the shoe, which further elevation increases the outward force against the bottom of the shoe and tends to return the roof to center. It can be seen, however, that movement of the roof toward and away 35 from the wall of the tank while increasing or decreasing the amount of elevation of the lever 17, causes substantially no vertical movement of the shoe. It can further be seen that the outward force exerted against the upper portion of the shoe by the shoe supporting member is nearly 40 constant regardless of the position of the roof with respect to the center of the tank.

In the embodiment shown in Fig. 3, the horizontal portion 25 of the shoe supporting member is pivotally connected to the inwardly extending portion 20 by means of a longitudinal slot 28 formed in the portion 25, which slot slidably engages a pin 29 fixed in the portion 20. A second slot 30 longitudinal of the vertical leg 25 is adapted to slidably engage a pin 31 fixed in the angle 19. This particular arrangement assures a reaction perpendicular to the long side of the slots (if friction be neglected), that is, the downward force upon the portion 20 by the shoe supporting member is always at right angles to the

slot 28, while the force pressing the vertical leg outwardly is likewise perpendicular to the slot 38 regardless of the degree of elevation of the lever 17. In the embodiment shown in Fig. 4, the shoe supporting member 22a is in the form of a straight member pivoted to the upper portion of the shoe and to the inwardly extending portion 20 of the lever.

While we have shown and described certain embodiments of our invention, it is to be understood that it is capable of many modifications. Changes, therefore, in the construction and arrangement may be made without departing from the spirit and scope of the invention as disclosed in the appended claims.

We claim:

1. In a floating roof tank having at least one shoe to slidably contact the side walls of the tank, means for pressing the shoe against the side walls including a substantially L-shaped lever having one leg swingably attached to the roof, and extending downwardly therefrom to the angle of the L with the other leg being weighted and extending inwardly from said angle, and shoe supporting means pivotally supported by said inwardly extending leg and connected to the shoe, said lever being elevated against gravity from a freely hanging position by inward pressure of the shoe thereagainst when the roof is centered in the tank.

2. Apparatus of the character described in claim 1 in which said shoe supporting means is connected to the upper portion of the shoe.

3. Apparatus of the character described in claim 1 in which said shoe supporting means is substantially in the form of an L having a substantially vertical leg connected to the upper portion of the shoe, and a substantially horizontal leg pivotally connected to the inwardly extending leg of the lever.

4. In a floating roof tank having at least one shoe to slidably contact the side walls of the tank, means for pressing the shoe against the side walls including a lever swingably attached to the roof, said lever having an angular portion, a portion extending downwardly from the point of attachment to the roof to the angular portion and a portion extending inwardly from said angle and shoe supporting means substantially in the form of an L having a substantially vertical leg connected to the upper portion of the shoe, and a substantially horizontal leg pivotally connected to the inwardly extending portion of the lever, means for exerting a downward force on said inwardly extending portion, said lever being elevated from a freely hanging position by inward pressure of the lower portion of the shoe thereagainst when the roof is centered in the tank.

5. Apparatus of the character described in claim 4 in which said shoe supporting member is pivotally connected to the inwardly extending portion of the lever by means of a pin fixed in said portion and adapted to slidably engage a longitudinal slot in said horizontal leg, said member being provided with a second slot longitudinal of the vertical leg thereof adapted to slidably engage a pin in said angle.

10 6. Apparatus of the character described in claim 4 in which said shoe supporting member exerts an outward force on the upper portion of the shoe equal to the inward pressure of the lower portion of the shoe against said lever, when the roof is centered in the tank.

15 7. Apparatus of the character described in claim 4 in which the inward pressure of the shoe against said lever varies inversely as the distance between the roof and the shoe and the shoe supporting member exerts a substantially constant outward force against the upper portion of the shoe.

20 8. In a floating roof tank having at least one shoe to slidably contact the sidewalls of the tank means for pressing the shoe against the sidewalls, including a substantially L shaped lever having one leg swingably attached to the roof and extending downwardly therefrom to the angle of the L, with the other leg being weighted and extending inwardly from said angle to swing said lever to bring said angle against the lower portion of the shoe and shoe supporting means pivotally supported by said inwardly extending leg and connected to the upper portion of the shoe, said lever being elevated against gravity from a freely hanging position by inward pressure of the shoe thereagainst when the roof is centered in the tank.
